Ms. 295

Washburn Race of Seneca Falls, N. Y.

Letters Patent No. 295. Dated June 25, 1850.

The Schedule referred to in these Letters Patent and making
part of the same.

To all whom it may concern:

Be it known that I,
Washburn Race of Seneca Falls in the county of Seneca
and State of New York, have invented, or produced,
a new and ornamental design for the top and bot-
tom plates of an air-tight stove; and I do hereby
declare that the accompanying drawings do clearly

represent the shape of the said plates, and the relief configurations upon the same, when taken in connection with this specification.

My said ornamental stove plates have an oval outline, and are intended to be combined with an oval sheet iron tube, by means of the flange h, descending from the under side of the top plate, and the oval depression i, in upper side of the bottom plate. Fig. 1. is a vertical section through the centre of both stove plates, the dotted vertical lines extending from one to the other representing the sheet iron tube with which the plates are intended to be combined. The top plate has an oval opening f, in its centre surrounded by a plain oval surface g; and outside of this plain surface g, the plate has three curves A. B. C. Fig. 2. represents the configurations on each curve of the top plate, which are indicated respectively by the corresponding letters A. B. C: the inner curve A, being ornamented by a representation of a wreath of roses, the curve B by a representation of foliage, and the curve C, by a representation of foliage and scroll work, with openings through the plate formed within each figure. The bottom plate has two curves D. E, between its central depression i, and its periphery, which are ornamented with relief configurations of the pattern represented by D. E, in Fig. 3.

What I claim as my invention and desire to secure by letter, is the design of the top and bottom stove plates represented in the accompanying drawings and herein set forth.

The above specification of my design
